UNITED STATES PATENT OFFICE

2,485,369

PUSH-PULL AMPLIFIER SYSTEM

Robert B. Dome, Geddes Township, Onondaga County, N. Y., assignor to General Electric Company, a corporation of New York

Application December 4, 1947, Serial No. 789,647

3 Claims. (Cl. 179—171)

1

My invention relates to push-pull amplifier systems and, more particularly, to such systems as may be driven by a single-ended source. It is a primary object of my invention to provide improved means for obtaining push-pull output from a single-ended source.

As it is well known in the art, it is desirable for high fidelity sound output to employ a push-pull out-put amplifier. In such systems as have been used in the past to obtain push-pull output from a single-ended source, the output capabilities of the push-pull amplifier have not been utilized to full advantage, since a series resistance has customarily been employed in the anode output circuit of one of the pair of output tubes in order to obtain a driving voltage of suitable phase for the control grid of the second output tube. Furthermore, some of the prior systems proposed have an inherent tendency toward self-oscillation due to regeneration. In addition, some of these systems are characterized by a certain amount of undesirable hum which appears at the loud speaker.

It is a particular object of my invention to provide a push-pull amplifier circuit which obtains improved output.

Another object of my invention is to provide such a system which is free of any tendency toward self-oscillation between the push-pull tubes as is sometimes encountered because of the similarity of the circuits to the Hartley oscillator.

Another object of my invention is to provide such an amplifier in which undesirable hum is substantially eliminated from the output.

A further object of my invention is to provide a push-pull amplifier, driven by a single-ended source, which employs a transformer in the anode circuit of the first tube to supply grid excitation for the second tube, thereby effecting an economy of parts.

The features of my invention which I believe to be novel are set forth with particularity in the appended claims. My invention itself, however, together with further objects and advantages thereof, may best be understood by reference to the following description taken in connection with the accompanying drawing, in which Fig. 1 is a schematic circuit diagram of a push-pull amplifier system which suitably embodies my invention, and Fig. 2 is a schematic diagram of another modification. Like numerals indicate like elements in the two figures.

Referring to Fig. 1, an electron discharge de-

2

vice 1 having cathode, anode, and control electrodes 2, 3, 4, respectively, serves as a single-ended audio amplifier. Audio-frequency signal voltage is applied to the control electrode 4 of device 1 from a suitable source 5, which may comprise the second detector of a superheterodyne receiver. The customary cathode bias resistor 6 and by-pass condenser 7 are provided between the cathode 2 of device 1 and the low potential side of the audio-frequency source 5, which is shown connected to ground. Positive direct operating voltage is applied to the anode 3 of device 1 from a suitable source, here shown as a battery 8, through the customary anode load resistance 9. The amplified audio-frequency output appearing across the load resistance 9 is coupled to the control electrode 10 of device 11, which is one of a pair of electron discharge devices 11, 12 by means of the customary coupling capacitance 13 and grid leak resistance 14. Devices 11, 12 are connected in push-pull, the cathodes 15, 16 being directly connected together and thence to ground through a common cathode bias resistance 17 and by-pass condenser 18. The screen grids 19, 20 of devices 11, 12 are directly connected together, positive direct screen operating voltages being supplied from a suitable source, here shown as a battery 21.

I provide an anode output circuit, comprising the parallel combination of the primary winding 22 of a conventional output transformer 23 and a capacitance 24, connected in series between the anodes 25, 26 of devices 11, 12 respectively. Also included in the anode circuit of device 11 is the primary winding 27 of an auxiliary transformer 28, shunted by a resistance 29. Suitable positive unidirectional operating potentials are supplied to the respective anodes 25, 26 from battery 21 through a tap 30 on the primary winding 22 of output transformer 23. The secondary winding 31 of output transformer 23 is connected to a suitable load, here shown as a loudspeaker 32. In order to obtain true push-pull operation, the secondary winding 33 of auxiliary transformer 28, being isolated from the primary winding 27 by an electrostatic shield 34, is connected between the control electrode 35 of device 12 and ground.

In operation, signals emanating from the audio-frequency source 5 are applied to the control grid 4 of device 1, and the amplified output is impressed on the control electrode 10 of device 11 in a manner well known in the art. The resulting variations in the anode current of device 11 set up audio voltages across resistance 29 which are 180-degrees out of phase with the grid voltage.

A corresponding audio voltage is induced across secondary winding 33 of auxiliary transformer 28 and applied to the control grid 35 of device 12. Since the respective control grid voltages of devices 11, 12 are always opposite in phase, the varying anode currents of devices 11, 12 combine in the primary winding 22 of the output transformer 23 to produce additive effects on the load current in push-pull fashion. The electrostatic shield 34 between the windings of the auxiliary transformer 28 is necessitated by the high audio-frequency potential difference between the windings.

It will be seen that the use of an auxiliary transformer to supply grid excitation voltage for the second tube eliminates the necessity of the customary coupling condenser and grid leak resistor. A further economy of parts is effected by using an output transformer 23 having a single-tapped primary winding shunted by a single condenser, instead of employing a circuit which uses two primary windings each shunted by a condenser. Furthermore, the use of a separate phase inverter tube is avoided.

A further advantage of the circuit of Fig. 1 is that any hum voltage appearing across the source of the direct operating potential is isolated from the control grid of the second tube by the auxiliary transformer. A still further advantage over a system utilizing a resistance in series with one half of the primary winding of the output transformer results from the low direct voltage drop in the primary winding of the auxiliary transformer. This provides an increased output from a given anode voltage supply. Furthermore, the system is inherently stable, there being very little tendency toward self-oscillation.

Referring to Fig. 2, a further modification is shown in which the auxiliary transformer is connected in the low potential side of the anode-cathode circuit. In this application, the parallel combination comprising resistance 29 and the primary winding 27 of the auxiliary transformer 28 is connected between the cathode 15 of device 11 and the cathode bias resistance 17 and by-pass condenser 18. In all other respects, the circuits of Fig. 1 and Fig. 2 are identical. By so locating the auxiliary transformer, the necessity of an electrostatic shield between the windings thereof is eliminated, since the primary 27 is no longer at a high audio-frequency potential with respect to the secondary 33. This arrangement also permits the use of a step-up transformer; thus, by proper design, the grid excitation voltage for device 12 may be made substantially the same in magnitude as that for device 11, and at the same time the impedance of the primary 27 may be made low so as to avoid serious degeneration in device 11. The use of step-up transformer also permits the value of resistance 29 to be decreased, thus providing a still further increase in the net audio-frequency output appearing at the loudspeaker 32 for a given excitation voltage at source 5. The magnitude of the grid excitation voltage applied to device 12 may be controlled by suitably adjusting the value of resistance 29.

While I have shown and described certain present preferred embodiments of my invention, it will be understood that numerous variations and modifications may be made, and I contemplate in the appended claims to cover any such vari-

ations and modifications as fall within the true spirit and scope of my invention.

What I claim as new and desire to secure by Letters Patent of the United States is:

- 5 1. In combination with a single-ended source of signal voltage, an electronic amplifier system comprising a pair of electron discharge devices connected in push-pull, said devices having respective anodes and control electrodes, said source being connected to the control electrode of one of said devices, means comprising a first transformer for coupling the output of said system to a useful load, a second transformer having a primary winding connected in the anode-cathode circuit of said one device and having a resistance in parallel therewith, and the secondary winding of said second transformer being connected between the control electrode of the other of said devices and ground, and means for applying substantially equal positive unidirectional operating potentials to said anodes.
- 10 2. In combination with a single-ended source of signal voltage, an electronic amplifier system comprising a pair of electron discharge devices connected in push-pull, said devices having respective anodes and control electrodes, said source being connected to the control electrode of one of said devices, a push-pull output circuit for said devices comprising a transformer having a primary winding and a secondary winding, said primary winding being connected in series with the anode of said one device, said secondary winding being connected between the control electrode of the other of said devices and the low potential side of said source, a resistance connected in parallel with said primary winding, and means for applying substantially equal positive direct operating potentials to said anodes.
- 15 3. In combination with a single-ended source of signal voltage, an electronic amplifier system comprising a pair of electron discharge devices connected in push-pull, said devices having respective cathodes, anodes, and control electrodes, said source being connected to the control electrode of one of said devices, an output circuit connected between said anodes, means comprising a transformer having primary and secondary windings for applying signal voltage to the control electrode of the other of said devices in proper phase for push-pull operation, said primary winding being connected in series between said cathodes and in parallel with a resistance, said secondary winding being connected between the control electrode of said second device and ground, and means for applying substantially equal positive unidirectional operating potentials to said anodes.
- 20 4. In combination with a single-ended source of signal voltage, an electronic amplifier system comprising a pair of electron discharge devices connected in push-pull, said devices having respective cathodes, anodes, and control electrodes, said source being connected to the control electrode of one of said devices, a push-pull output circuit for said devices comprising a transformer having a primary winding and a secondary winding, said primary winding being connected in series with the anode of said one device, said secondary winding being connected between the control electrode of the other of said devices and the low potential side of said source, a resistance connected in parallel with said primary winding, and means for applying substantially equal positive direct operating potentials to said anodes.
- 25 5. In combination with a single-ended source of signal voltage, an electronic amplifier system comprising a pair of electron discharge devices connected in push-pull, said devices having respective cathodes, anodes, and control electrodes, said source being connected to the control electrode of one of said devices, a push-pull output circuit for said devices comprising a transformer having a primary winding and a secondary winding, said primary winding being connected in series with the anode of said one device, said secondary winding being connected between the control electrode of the other of said devices and the low potential side of said source, a resistance connected in parallel with said primary winding, and means for applying substantially equal positive direct operating potentials to said anodes.
- 30 6. In combination with a single-ended source of signal voltage, an electronic amplifier system comprising a pair of electron discharge devices connected in push-pull, said devices having respective cathodes, anodes, and control electrodes, said source being connected to the control electrode of one of said devices, a push-pull output circuit for said devices comprising a transformer having a primary winding and a secondary winding, said primary winding being connected in series with the anode of said one device, said secondary winding being connected between the control electrode of the other of said devices and the low potential side of said source, a resistance connected in parallel with said primary winding, and means for applying substantially equal positive direct operating potentials to said anodes.
- 35 7. In combination with a single-ended source of signal voltage, an electronic amplifier system comprising a pair of electron discharge devices connected in push-pull, said devices having respective cathodes, anodes, and control electrodes, said source being connected to the control electrode of one of said devices, a push-pull output circuit for said devices comprising a transformer having a primary winding and a secondary winding, said primary winding being connected in series with the anode of said one device, said secondary winding being connected between the control electrode of the other of said devices and the low potential side of said source, a resistance connected in parallel with said primary winding, and means for applying substantially equal positive direct operating potentials to said anodes.
- 40 8. In combination with a single-ended source of signal voltage, an electronic amplifier system comprising a pair of electron discharge devices connected in push-pull, said devices having respective cathodes, anodes, and control electrodes, said source being connected to the control electrode of one of said devices, a push-pull output circuit for said devices comprising a transformer having a primary winding and a secondary winding, said primary winding being connected in series with the anode of said one device, said secondary winding being connected between the control electrode of the other of said devices and the low potential side of said source, a resistance connected in parallel with said primary winding, and means for applying substantially equal positive direct operating potentials to said anodes.
- 45 9. In combination with a single-ended source of signal voltage, an electronic amplifier system comprising a pair of electron discharge devices connected in push-pull, said devices having respective cathodes, anodes, and control electrodes, said source being connected to the control electrode of one of said devices, a push-pull output circuit for said devices comprising a transformer having a primary winding and a secondary winding, said primary winding being connected in series with the anode of said one device, said secondary winding being connected between the control electrode of the other of said devices and the low potential side of said source, a resistance connected in parallel with said primary winding, and means for applying substantially equal positive direct operating potentials to said anodes.
- 50 10. In combination with a single-ended source of signal voltage, an electronic amplifier system comprising a pair of electron discharge devices connected in push-pull, said devices having respective cathodes, anodes, and control electrodes, said source being connected to the control electrode of one of said devices, a push-pull output circuit for said devices comprising a transformer having a primary winding and a secondary winding, said primary winding being connected in series with the anode of said one device, said secondary winding being connected between the control electrode of the other of said devices and the low potential side of said source, a resistance connected in parallel with said primary winding, and means for applying substantially equal positive direct operating potentials to said anodes.
- 55 11. In combination with a single-ended source of signal voltage, an electronic amplifier system comprising a pair of electron discharge devices connected in push-pull, said devices having respective cathodes, anodes, and control electrodes, said source being connected to the control electrode of one of said devices, a push-pull output circuit for said devices comprising a transformer having a primary winding and a secondary winding, said primary winding being connected in series with the anode of said one device, said secondary winding being connected between the control electrode of the other of said devices and the low potential side of said source, a resistance connected in parallel with said primary winding, and means for applying substantially equal positive direct operating potentials to said anodes.
